UNITED STATES PATENT OFFICE.

JOSEPH F. RICHMOND, OF FORT LEAVENWORTH, KANSAS.

HUMIDIFIER.

Application filed June 10, 1926. Serial No. 115,046.

This invention relates to humidifying devices such as are used in connection with humidors, show cases, or other containers wherein tobacco, cigarettes, or cigars are 5 kept or in any place where it is desired to keep articles moist.

The general object of the invention is to provide a jar having a wick formed to provide a relatively large water absorbing and 10 diffusing surface and provide means for supporting the wick on the jar to thereby provide a moistener which will require very little attention and which will keep an even amount of moisture in the container within 15 which the jar is placed.

A further object is to provide a device of this kind which even when overturned will not spill out the water therein before the jar can be righted.

20 A still further object is to provide a device of this character which is very simple, may be cheaply made, is convenient in use, and is thoroughly effective for the purpose intended.

25 My invention is illustrated in the accompanying drawings wherein:—

Figure 1 is a sectional view of a humidifier constructed in accordance with my invention;

30 Fig. 2 is a perspective view of the supporting plate;

Fig. 3 is a perspective view of the wick and absorbent member.

Referring to these drawings 10 designates 35 a jar designed to contain water. It may be made of glass, tin or any other non-rustable material. This jar is shown as having a screw-threaded upper end to receive a lid but may be made in any other manner. The 40 jar is provided preferably with a filling neck 11 normally closed by a screw-threaded or other cap or stopper 12.

Adapted to engage with the screw-threads 45 of the jar is an annular cap 13 having a relatively large opening in the center of the cap and adapted to rest upon the top of the jar beneath the cap is a supporting plate 14 having either a plurality of openings or a central opening 15. Resting upon this 50 supporting plate is an absorbant member 16 which may be made of blotting paper, very absorbent textile fabric or material like wicking. This is supported by the plate 14 and is clamped down upon the plate by 55 means of the annular top 13. A wick 17 extends downward into the water, from the

absorbent member 16, within the jar. This wick may be made of material like darning cotton or any other material which will carry water. Preferably the absorbent member 60 16 will be formed of two thicknesses of material and the wick 17 will pass through the lower thickness of material and be knitted or otherwise attached to the absorbent member and this joint will be 65 covered by the upper layer of material. It will be understood, however, that if this absorbent member 16 is made of wicking as, for instance, soft darning cotton, it will be 70 in one thickness. Of course, the supporting 75 plate 14 will be of aluminum or some other nonrustable material. While I have illustrated the top 13 as being screw-threaded it is to be understood that any other suitable joint might be used between this top 13 and 80 the jar in order to hold the top 13 in place and against any accidental displacement. I do not wish to be limited to the illustrated shape of the jar as this might be made 85 square, triangular, or have any other convenient shape.

The jar is to be filled with water to about 1/2" of the top. The absorbent disk 16 is disposed upon the plate 14 and these disposed upon the top of the jar and then the 85 top 13 is screwed in place. The absorbent member 16 presents a relatively large area to the air and thus diffuses a relatively large amount of moisture within the cigar or tobacco case and keeps an even amount of 90 moisture in the tobacco. Inasmuch as the wick 17 is relatively small but extends down to the bottom of the jar, the jar will contain a large amount of water and will, therefore, not have to be filled more than about once a 95 month whereas the ordinary sponge moistener requires to be filled relatively often. Furthermore, if this jar be overturned, the water will not spill out of the jar for some time whereas the ordinary moistener if tipped over will immediately discharge its 100 contents. With my moistener also the top of the jar is entirely covered so that nothing can drop into the water.

The wick 17 must be very loose and soft 105 and any number of wicks may be used if it is desired to increase the flow of water to the blotter or other absorbent pad 16. I have illustrated a filling neck 11, but it is to be understood that no filling neck need be 110 used and indeed this would not be desirable on large sized jars.

I claim:—

A moistener for humidores comprising a container, a supporting plate having an aperture and adapted to be disposed upon the top of the container, a fibrous water absorbing element resting upon said plate and having a wick threaded through the fibrous element and extending downward into the

container, a second fibrous element superimposed upon the first-named element and covering the exposed portions of the wick and means for clamping the fibrous element to the plate on the top of the container.

In testimony whereof I hereunto affix my signature.

JOSEPH F. RICHMOND.
